UNITED STATES PATENT OFFICE.

ELIZABETH M. SUTHERLAND, OF KANSAS CITY, MISSOURI.

GARMENT-HANGER.

1,291,242.

Specification of Letters Patent. Patented Jan. 14, 1919.

Application filed January 30, 1918. Serial No. 214,513.

To all whom it may concern:

Be it known that I, ELIZABETH M. SUTHERLAND, a citizen of the United States of America, residing at Kansas City, in the county of Jackson and State of Missouri, have invented new and useful Improvements in Garment-Hangers, of which the following is a specification.

As a garment hanger, the invention seeks 10 to provide, as its principal object, a device of this kind having two T-shaped members hingedly connected together and a flat V-shaped spring partly surrounding the hinged connection and bearing upon the 15 two members, this spring tending to keep those ends of the members composing the cross legs of the T's in contact with each other.

A further object of the invention is to 20 provide means for attaching the V-shaped spring in such a way that it may be easily detached without the disengagement of the two members, thereby providing means for the convenient replacing of a tired or 25 damaged spring with a new one.

A still further object makes provision for 30 the inversion of the V-shaped spring to hold the T-shaped members normally apart, so that a garment may be supported by the device in a manner similar to the way in which 35 the garment is supported on the body, this arrangement being conducive to the drying of the garment, should it be damp or wet.

A still further object of the invention is 40 to provide a device of this kind which is simple in construction, durable and effective in operation and which may be manufactured at low cost.

Still other and further objects will appear as the invention is set forth in detail 45 in the description which follows.

The embodiment in which the invention is 50 shown in the accompanying drawings is at present thought to be the most efficient but the actual reduction to practice may show certain changes and alteration to be of advantage. The right, therefore, is reserved to make such changes or alterations in so far as they may be compatible with the 55 spirit of the subjoined claim.

In the accompanying drawings:

Figure 1 is a perspective view of the invention, showing the manner of application.

Fig. 2 is a central vertical sectional view. 55 Fig. 3 is a perspective view of the V-shaped spring member employed to keep the

two members composing the hanger normally together.

Fig. 4 is a side view of the invention showing a second method of application. 60

Referring to the drawings, the invention is shown in the application of securing the skirt 1, so that the latter may be conveniently hung in a wardrobe or cupboard without exposing it to the danger of being wrinkled. 65

The hanger by which the skirt is hung comprises two T-shaped members 2 and 3, the cross legs 4 of which constitute clamping jaws for the skirt, or trousers, or whatever other piece of wearing apparel it is 70 desired to hang neatly in a cupboard.

On the vertical legs of the T-shaped members 2 and 3 at specified points above the cross legs or jaw members 4, there are formed ears 5 and 6, the ears 5 being attached to the member 2 and the ears 6 to the member 3. The pair of ears on each member obtain in a plane at right angles to the plane of that member and the two ears 5 on the member 2 are the requisite distance 75 apart to permit them to abut on the inside the two ears 6 of the member 3. The members 2 and 3 are hingedly connected together by means of these ears and a pin 7 extending transversely across the vertical 80 legs of the two members effects a pivot connection between each pair of the two adjacent ears 5 and 6.

The upper ends of the vertical legs of the 85 two members 2 and 3, are diagonally disposed with respect to the remainder of the legs. Beginning at points just above the ears 5 and 6, these two upper ends diverge, the upper end of member 2 terminating at a suitable point above the ears to leave the 90 upper end a suitable length to permit said upper end a suitable length to permit the member to have its lower jaw separated from the lower jaw of the member 3 by pressure exerted by the finger on the upper end. The upper end of the vertical leg 100 of the member 3 exceeds the length of the upper end of the member 2 by a sufficient amount to permit the forming thereon of a hook 8 by means of which the device as a whole may be conveniently hung on the hook 105 of the wardrobe.

To provide means for keeping the jaw 4 normally together a V-shaped spring 9 is provided. This spring is so positioned that the pin 7 engages in the crotch between its 110 two legs, the legs of the spring rising and bearing against the upper ends of the ver-

tical legs of the members 2 and 3 at points just above the ears 5 and 6 formed thereon. The spring 9 is of such a width that it may conveniently stand between the two ears 5 and its legs, near their free ends, have each a protuberance 10 formed by the proper shaping of the metal of which the spring is made. The diverging upper ends of the vertical legs of the members 2 and 3 have each formed by their inner face a projection 11 so positioned that the protuberance 10 of the adjacent leg of the spring 9 may stand above it. These two projections 11 in conjunction with the protuberances 10 tend to keep the spring 9 in place.

It will be observed that the pressure exerted by the fingers on the diverging ends of the members 2 and 3 will result in the separation of their jaw members 4 against the pressure of the spring 9, the spring 9 tending normally to keep the jaw members 4 in contact and in a clamped position on any wearing apparel which the device as a whole is designed to support.

In the event that the spring 9 should become damaged or weakened as a result of continued use, it may be conveniently removed and replaced with a new spring, the removal of the spring consisting only in pressing its free ends toward each other until the protuberances 10 may be disengaged from the projections 11, after which the removal may be completed by withdrawing the spring from below the pin 7.

It will be observed that this removal of

the spring is effected without disconnecting the hinged connection between the two members 2 and 3, as would be necessary with a coiled spring which, to be held in place, would necessitate the pin 7 being passed through the coiled portion.

Withdrawing the spring as aforesaid, inverting it and re-attaching it in the inverted position to the two members 2 and 3, as shown in Fig. 4, will result in holding the two jaw members 4 normally apart, a convenient position of the jaw members for holding a garment distended, so that it may readily dry, if damp or wet.

The invention having been described, what is claimed as new and useful is:

The garment hanger comprising a pair of T-shaped clamping members each formed with ears near the end of its leg, a pintle engaging the ears and pivotally connecting the clamping members together, the legs being formed with projections above the pivotal connection, and a V-shaped spring straddling the pintle and formed with bulges engageable above the projection, the legs of the spring bearing against the legs of the clamping members to keep the jaws thereof together, the spring being invertible in position so that its ends may bear against the legs of the clamping members below the pivotal connection, to force the jaws of the same apart.

In testimony whereof I affix my signature,

ELIZABETH M. SUTHERLAND.
